UNITED STATES PATENT OFFICE

154,923

DESIGN FOR A SOAP HOLDER

George C. Heliote, Oakland, Calif.

Application February 24, 1943, Serial No. 144,708

Term of patent 14 years

(Cl. D4—3)

To all whom it may concern:

Be it known that I, George C. Heliote, a citizen of the United States and a resident of Oakland, county of Alameda, and State of California, have invented a new, original, and ornamental Design for a Soap Holder, of which the following is a specification, reference being had to the accompanying drawing, forming part thereof.

I claim:

The ornamental design for a soap holder, substantially as shown.

GEORGE C. HELIOTE.
